UNITED STATES PATENT OFFICE.

MAX A. BUCH, OF DETROIT, MICHIGAN.

REMOVABLE WINDOW STRUCTURE FOR AUTOMOBILES.

1,249,897.

Specification of Letters Patent. Patented Dec. 11, 1917.

Application filed March 24, 1917. Serial No. 157,066.

To all whom it may concern:

Be it known that I, MAX A. BUCH, a subject of the Emperor of Germany, residing at Detroit, county of Wayne, State of Michigan, have invented a certain new and useful Improvement in Removable Window Structures for Automobiles, and declare the following to be a full, clear, and exact description of the same, such as will enable others skilled in the art to which it pertains to make and use the same, reference being had to the accompanying drawings, which form a part of this specification.

This invention relates to removable window structures for automobiles.

The necessity of providing a removable window structure in place of curtains for winter use has been lately quite generally recognized, and efforts have been made along this line.

It is the object of the present invention to provide a unit window structure for each side, which can be very readily applied to an ordinary collapsing top or folding hood. The windows are arranged so that they slide longitudinally of the vehicle to allow egress or ingress from or into either the front or rear seats. This will more fully appear in the specification following.

30 In the drawings,

Figure 1 is a side elevation of the unit window structure of the two-sash type showing it applied to a collapsible top.

Fig. 2 is a longitudinal section on the line 35 2, 2 of Fig. 1.

Fig. 3 is a longitudinal section on the line 3, 3 of Fig. 1.

Fig. 4 is a side elevation of the three-sash unit.

40 Fig. 5 is a longitudinal section on the line 5, 5 of Fig. 4.

Fig. 6 is a vertical cross section through the three panels where they overlap.

Fig. 7 is a vertical cross section through 45 the center post and through the overlapping windows shown in Fig. 1.

The panels or sashes in each form of construction are arranged to slide on telescoping rods *a*. Take, for instance, the two-sash type, the front end of the outer telescoping section is provided with threads for screwing into the windshield post *b* and the inner telescoping section is provided with a slot adapted to fit over the turn-button *c* 55 on the rear bow. This, it will be evident, very quickly fits the unit to the car as the

center post *d* is provided with the dowel pins *e* which drop into the dowel holes in the top of the body. It will be noted that this center post *d* is made of two uprights, 60 one a thin outer upright *f* and the other an inner thicker upright *g*, the two being spaced from each other to allow the front sash *h* and the rear sash *i* to slide between them.

The front sash *h* is provided with a bracket *j* which slides on the telescoping rod *a* and is provided with a rear bracket *k* which runs over the top of the rear sash and engages with the inner section of the telescoping rod. The rear or inner sash *i* is provided with a front bracket *m* and a rear bracket *n* which engage the telescoping rod.

It will be noted that the telescoping rod passes through the inner upright *g*, and this member acts as a support for the telescoping rod where the two sections join. On the top of the center post *d* is provided a pivoted clip *o* which may be swung down over the forward outrigger bow of the one-man top to steady the post *d* at the top.

At the bottom of the sashes are a pair of movable telescoping rods, that is to say, the sections of these rods move in and out when the windows are slid back and forth. These sections are depicted in Fig. 3. It will be seen that the inner solid rod *p* is fastened at its rear end to the rear of the rear sash *i* and at its front end engages in the outer or sleeve-like section *q*, which is fastened 90 at its front end to the front end of the front sash *h*. The front end of the rear sash *i* is provided with a slotted bracket *r* which slides on the outside of the tubular telescoping section *q*.

In Figs. 4, 5 and 6 the three-sash type embodying my invention is shown. In this form of construction in place of the center pillar, a center sash *s* is used. This is provided with brackets having set screws *t* 100 which fit on to the inside of the bow construction at the top and the dowel pins and dowel holes are provided at the bottom. The top and bottom sash rails of the front and rear windows are provided with longitudinal bores so as to make these sashes slidable on telescoping rods *a*, *a*, which are in the case of the three-sash construction, two in number, and whose inner ends are fastened to brackets *u* on the inside of the 105 center sash. At the bottom in the three sash unit, the rod sections are not fastened to

the car at the front and rear but slide with the sashes, as indicated in connection with the two sash unit.

What I claim is:

- 5 1. In a removable glass side structure for vehicle bodies, the combination of an extensible rod removably securable between the windshield and the rear of the top, a center member for supporting the rod, and sashes 10 slidable with respect to said center member and into overlapped relation upon the extensible rod.
- 15 2. In a removable glass side structure for vehicle bodies, the combination of an extensible rod for fitting between the windshield and the rear of the top, a center member supporting the middle of the rod, sashes 20 slidable upon the extensible rod with respect to the center member and into overlapped relation, and means for detachably securing the center member to the body.
- 20 3. In a removable glass side structure for

vehicle bodies, the combination of an extensible rod which can be fitted between the windshield and the rear of the top, a center member 25 for upholding the middle of the rod and provided with means for engaging the bow structure at the top and means for detachably engaging the body at the bottom, and sliding sashes sliding through the center member and sliding upon the extensible rod.

4. In a removable glass side structure for vehicle bodies, the combination of an extensible rod fitted between the windshield 35 and the rear of the top, sliding sashes provided with brackets at the top adapted to slide on said extensible rod, and rods at the bottom of the sashes some of whose sections 40 are telescoping and are fastened to the sashes so as to slide in and out with the sashes.

In testimony whereof, I sign this specification.

MAX A. BUCH.
